UNITED STATES PATENT OFFICE.

IRA G. MITCHELL, OF MEEKER, COLORADO, ASSIGNOR OF ONE-TWELFTH TO ARTHUR C. MOULTON, ONE-TWELFTH TO FRANK E. SHERIDEN, ONE-TWELFTH TO REUBEN S. BALL, ONE-TWELFTH TO LEE PETERSON, ONE-TWELFTH TO FRANK H. JO HANTGEN, AND ONE-TWELFTH TO GEORGE E. AICHER, OF MEEKER, COLORADO.

ADJUSTABLE CRANK-DISK.

No. 811,426.

Specification of Letters Patent.

Patented Jan. 30, 1906.

Application filed May 16, 1905. Serial No. 260,457.

To all whom it may concern:

Be it known that I, IRA G. MITCHELL, a citizen of the United States, residing at Meeker, in the county of Rio Blanco and State of Colorado, have invented certain new and useful Improvements in Adjustable Crank-Disks, of which the following is a specification, reference being had therein to the accompanying drawings.

10 My invention relates to machine elements, and more particularly to an adjustable crank disk or wheel for use on engines or like machinery where crank motion, piston, pitman, or connecting-rods are used to transmit motion of any kind, whether rotary, sliding, oscillating, or gyrating, one of the objects being to provide a device of the character described which shall be useful in varying, lengthening, shortening, strengthening, or perfectly adjusting the length of the stroke with a single disk or wheel by turning my eccentric-disk with crank-pin to or from the center.

Other objects and advantages of my invention, as well as the structural features by 25 means of which these objects are attained, will be made clear by an examination of the specification, taken in connection with the accompanying drawings, in which the same reference-numerals indicate corresponding portions throughout, and in which—

Figure 1 is a side elevation of a disk, showing my invention in operative position. Fig. 2 is a vertical section, and Fig. 3 is a perspective view of the eccentric-disk.

35 1 designates a disk or wheel which may be made of any desired size or material and preferably formed solid, as shown in the drawings. This disk is provided with a central opening 2, whereby it may be mounted on a driving-shaft, and a groove or kerf 3 longitudinal of the opening 2 for the reception of a key.

40 4 designates an adjustable eccentric-disk provided with a flange or lip 5 and a kerf or groove 6 in the center of its periphery. Set in an opening 7 in said eccentric-disk 4 is a crank-pin 8, engaged by a set-screw 9, whereby it is removably secured in operative position and held against rotation. This crank-50 pin is provided with flanges or rings 10, by

means of which a crank or piston may be held in operative position thereon.

The disk 4 is adapted to rotate in a circular opening 11 through the disk or wheel 1 eccentric of its center, the flange 5 resting against a shoulder 12. A set-screw 13 of well-known construction and provided with a jam-nut 14 is screwed into a threaded opening 15 in the periphery of the disk 1, so that its lower end passes into and rests in the groove 6, thus holding the disk 4 in rotatable position in the circular opening 11. The disk is also provided with notches or holes 16 in one of its sides for the reception of the jaws of a wrench to be used in removing the disk provided it sticks in the opening.

17 designates a set-screw passing through the hub 18 of the disk 1, whereby said disk may be more securely keyed on the shaft, if found necessary.

In operation a crank-shaft is operably mounted on the crank-pin 10, which may either rotate in the eccentric-disk 4 or be held against rotation by the set-screw 9. The eccentric-disk 4 may rotate in the opening 11 or may be held against rotation by tightening the set-screw 13 and the jam-nut 15. In the largest-sized disks it may be found necessary to employ more than one set-screw and jam-nut in order to hold the eccentric-disk 4 against rotation. The flange 5 acts as a guard when bearing against the shoulder 12 and tends to aid in holding the eccentric 4 securely in place in the opening 11. By means of the adjustable features of the mechanism 85 hereinbefore described rotary, sliding, oscillating, or gyrating motion may be transmitted to engines or other machinery by means of pistons, pitmen, or other connecting-rods mounted on the crank-pin 8. This motion 9 may be controlled, varied, lengthened, or shortened, and the length of stroke may be perfectly adjusted by turning the eccentric-disk to or from the center, as may be found desirable.

Having thus described my said invention, what I claim as new, and desire to secure by Letters Patent of the United States, is—

1. A cylindrical body having a recessed portion in combination with an eccentric- 100

disk mounted in said recessed portion, said eccentric-disk being provided with an annular flange adapted to engage the recess of said annular body.

5. 2. A circular body having a recessed portion provided with an offset, in combination with an eccentric-disk rotatably mounted in said recessed portion, said eccentric-disk being provided with an annular flange adapted 10 to engage the offset in said annular body.

10. 3. A cylindrical body having a recessed portion, in combination with an eccentric-

disk rotatably mounted in said recessed portion, said eccentric-disk being provided with a peripheral groove and an annular rib, said rib being adapted to engage the recess of said cylindrical body, and means carried by said cylindrical body adapted to enter said groove.

In testimony whereof I hereunto affix my signature in presence of two witnesses.

IRA G. MITCHELL.
